UNITED STATES PATENT OFFICE.

JOHN ANTAL, OF BROOKLYN, NEW YORK.

DESIGN FOR JEWEL CASE.

Application filed June 22, 1922. Serial No. 2,770. Term of patent 3½ years.

To all whom it may concern:

Be it known that I, JOHN ANTAL, a citizen of Hungary, residing at Brooklyn, New York, in the county of Kings and State of New York, have invented a new, original, and ornamental Design for a Jewel Case, of which the following is a specification, references being had to the accompanying drawing, forming a part thereof.

The figures show two views of a jewel case embodying my design.

Fig. 1 is a side elevation, and Fig. 2 is an end elevational view of the same.

I claim:

The ornamental design for a jewel case as shown.

JOHN ANTAL.
